UNITED STATES PATENT OFFICE.

JULIUS SCHIRRA, OF PITTSBURG, PENNSYLVANIA, ASSIGNOR OF TWO-THIRDS TO MORGAN B. HALL AND WILLIAM C. RAE, OF ALLEGHENY PENNSYLVANIA.

ANCHORING DEVICE FOR CONCRETE CONSTRUCTION.

No. 831,804.

Specification of Letters Patent.

Patented Sept. 25, 1906.

Application filed September 13, 1904. Serial No. 224,241.

To all whom it may concern:

Be it known that I, JULIUS SCHIRRA, a citizen of the United States, residing at Pittsburgh, in the county of Allegheny and State of Pennsylvania, have invented certain new and useful Improvements in Anchoring Devices for Concrete Construction, of which the following is a specification, reference being had therein to the accompanying drawings, forming part of the specification, in which—

Figure 1 is a vertical cross-sectional view of a portion of floor construction embodying my improved anchoring devices. Fig. 2 is a partial cross-section thereof on the line II II of Fig. 1. Fig. 3 is a plan view of one complete bar provided with assembled anchors. Fig. 4 is a partial side elevation thereof. Fig. 5 is an end view. Fig. 6 is a similar view showing a supplemental securing-clip. Fig. 7 is a detail perspective view of one of the anchors detached. Fig. 8 is a similar view of one of the clips. Fig. 9 is a detail view illustrating a corrugated extremity.

My invention refers to improvements in means for binding or anchoring cement or concrete, and is particularly adapted for incorporation therewith in buildings, bridges, or other similar structures; and it consists of a supporting-bar or similar element provided with one or more attached anchoring devices having extremities arranged in such a manner as to extend in various directions, so that when embedded in the concrete they will engage and maintain therewith a firm binding hold. The bars are designed to be incorporated with the structural elements of the building and to form a partial support for the concrete, being arranged sufficiently near together so that when the concrete is hardened they will become permanent portions of the concrete structure.

Referring to the drawings, 2 represents the I-beams or other structural elements forming the framework of the building with which the floor is incorporated and between which the cement or concrete filling 3 is placed in the usual manner.

4 represents a bar of light structural shape, as a T, angle, I-beam, channel, &c., adapted to be arranged between and supported upon the flanges of any two adjacent beams, as shown in Fig. 1, the bar 4 being provided with one or more, preferably several, anchors

5. As shown in the drawings, these anchors are formed of strips of sheet metal split at the ends and separated so as to provide divergent extremities 6 at each side of the bar 4, around which the strip is bent and to which it conforms, as clearly shown. As thus constructed, several of these anchors are assembled along the bar and adjusted to proper location, and when the flooring material 3 is filled in they will become embedded and operate to firmly bind together and support the floor in the manner referred to.

In Fig. 6 I have shown clip 7 bent around in U form adapted to embrace the web portion of the beam 4 and provided with outwardly-extending extremities 8, having slots or openings 9, through which the extremities 6 are passed and then bent over and separated outwardly, as shown. By this construction they are more securely connected with the bar, and the clip also provides additional holding elements for the cement.

It will be understood that the anchors may be made in different designs or forms and that the number of extremities may be varied, but such constructions are considered to be within the scope of the invention and claims. The extremities 6 and 8 may, if desired, be corrugated or bent in any manner so as to provide roughened holding-faces, thus increasing the efficiency and binding hold, as in Fig. 9. As will be readily seen, the anchors may be adjusted longitudinally of the bar, and, if desired, may be secured in position in any suitable manner, as by riveting or otherwise.

A special advantage of the invention is that the parts may be shipped separately in very compact packages or in bulk and readily and easily assembled at the point of use, while the number of anchors to be used on a single bar may be varied within the judgment of the user.

The device is very simple in construction, economical in cost, being made out of sheet metal without waste, and performs its functions in a satisfactory and efficient manner.

Having described my invention, what I claim is—

1. The combination with a supporting-bar, of a sheet-metal anchoring device bent to embrace the supporting-bar and provided with oppositely-disposed diverging holding ex-

tr-mities, and a holding-clip arranged to embrace the other side of the bar and provided with terminals engaging said anchoring device, substantially as set forth.

- 5 2. An anchoring device consisting of a sheet-metal clip bent to conform to a supporting-bar and having oppositely-disposed diverging holding extremities, with a holding-clip adapted to surround the other side of the
10 bar and provided with portions arranged to engage said extremities and to bind them to said bar, substantially as set forth.
3. The combination with a supporting-bar,

of a series of holding-anchors mounted thereon consisting of sheet-metal strips bent to embrace the bar and having outwardly-extending diverging extremities, with holding-clips adapted to embrace the bar on its opposite side and to engage said extremities, substantially as set forth. 15

In testimony whereof I affix my signature in presence of two witnesses.

JULIUS SCHIRRA.
